UNITED STATES PATENT OFFICE.

CYRUS CHAMBERS, JR., OF PHILADELPHIA, PENNSYLVANIA.

BRICK-MACHINE

Specification forming part of Letters Patent No. 40,221, dated October 6, 1863.

To all whom it may concern:

Be it known that I, CYRUS CHAMBERS, Jr., of the city of Philadelphia, in the State of Pennsylvania, have invented a new and Improved Brick-Machine; and I do hereby declare the following to be a full and correct description of the same, reference being had to the accompanying drawings, in which—

Figure 1 is a vertical central longitudinal section of the machine. Fig. 2 is a top view of the same; Figs. 3, 4, and 5, detailed view of the dies. Fig. 6 is a side elevation, on an enlarged scale, of the knife-guide. Fig. 7 is an end view of the fly-wheel, knife, and knife-guide. Fig. 8 is a side view of the knife with its holder and spring, the knife being shown in two positions. Fig. 9 is a side view of the conical screw, showing its extra thread. Fig. 10 is a view of the inclined plane or guide. Fig. 11 is a central longitudinal section of the screw, its shell or case, and the compressing and forming dies. Fig. 12 is a top view of the stationary plate. Fig. 13, Sheet 2, is a perspective view of the machine complete and in operation.

The same part is indicated by the same letter of reference wherever it occurs.

The nature of my invention consists in certain improvements, hereinafter particularly described and shown, in that class of brick-machines in which the clay is forced through a die in a continuous stream, and afterward cut into the proper lengths to form bricks. Machines of this general character are in common use in England and France, and are more especially used in the production of hollow or perforated bricks. The bricks made by these machines in Europe are not remarkable for density or fine finish, the corners and edges being apt to present a ragged appearance. Moreover, the mode of cutting the bar of clay into bricks by a knife or wire passing rigidly in a plane at right angles to the course of the clay, but not moving with it or affected by its motion, had the effect to interfere with the shape of the brick and prevent its being exactly rectangular. In these machines the means used to propel the clay are the plunger or reciprocating piston, or the double or single spiral flange or screw working in a chamber of equal diameter throughout. In most, if not all, of them the clay used has been already

carefully pugged in another machine, usually an ordinary pug-mill, and all foreign substances carefully removed to avoid danger to the dies, and to secure as much as possible that exclusion of air and uniformity of texture which are essential to the perfection of brick-making by this mode; but even with this precaution, which adds the expense of a double handling to the manufacturer, the bricks are not solid or smooth on the corner or angles.

The object of my invention is to remedy as far as possible the defects of this mode of manufacture, while securing the great and obvious advantages of rapidity and consequent cheapness. The first step in this direction is the connection of the pugging mill or chamber with the machine in such a way that the pugging or comminution of the clay is performed in the same chamber from which the clay passes without change of direction to the dies and by the operation of the same machinery. The next step was so to modify the shape of the pugging-chamber that the clay in its passage toward the dies is very gradually compressed and freed from air, thus being rendered by the same process more dense and more plastic. My next step consisted in so constructing the propelling spiral flange or screw as to preserve the homogeneity of the structure of the clay or arrangement of the particles by preventing its arranging itself in those concentric or other layers which impart to it a striated appearance when burned and give it a tendency to break in the lines of the laminæ, whatever they may be, instead of having an even fracture in any desired direction under the operation of the trowel.

To prevent the machine from being overstrained, should a stone or other obstruction get into the die or threads of the screw, and thus prevent the passage of the clay, or should the pugging-knives feed the clay to the screw faster than it will receive it, I have attached a safety-valve, V³, at the end of the tempering-case, so weighted as to prevent the clay from exuding during the ordinary operation of the machine, but capable of being raised by the force of the clay when the pressure from any cause becomes greater than is desired. There is also a hand or "man hole," V⁴, in the screw-case for the purpose of taking out the stones that may lodge in the threads

of the screw. The die is hinged, so as to be readily opened to remove any foreign substance that may lodge in it.

My next improvement had for its object to secure, by a new arrangement of the matter, smooth and unbroken edges and corners to the bricks. Reflection will show that the ordinary operation of a plunger or other propelling device in a machine with an ordinary die is to produce the greatest amount of velocity in the center of the mass, giving the outer edges and surfaces less, and hence more liable to be rendered ragged and broken by partial adhesion to the die while passing through it. The remedy for this is to be sought in a reversal of the ordinary disposition of the material, forcing the greatest amount of clay into the edges and corners of the brick and compressing it there, so that the last action of the die upon it will be to give it smoothness instead of tearing it and rendering it rough and ragged. The peculiar form of my die completely effects this object.

The continuous moving bar of clay, as it passes from the die should present a smooth dense rectangular parallelopiped, with sharp well-defined angles or corners. It has then only to be cut into proper lengths to form perfectly-shaped bricks. To cut this bar while moving at right angles to its length, so that the end superficies of the bricks shall be planes exactly at right angles to the planes of the sides, is a practical problem of some nicety. The mode of solving it which I have devised is to let the cutter move laterally exactly at the same rate as the clay, which is accomplished by an adjustable inclined plane secured in such a position as to move the knife and its guide forward, with the bar during the severance of the clay. The division of the bar of clay into bricks exactly even lengths is effected by making the bar itself control the knife which divides it. The bricks thus served would be inconvenient to handle if they were not separated from each other by a greater interval than the width of the serving-knife. To secure this separation, I gear the off-bearing apron which receives the bricks so as to move faster than the apron which supports the uncut bar.

The foregoing observations will fully explain the principles by which I have been guided in the construction of my improved machine, and will best illustrate the nature of the invention and in what manner it is to be distinguished from others of the same general class.

To enable others skilled in the art to make and use my improved machine, I will proceed to a more particular description of its construction and operation, referring to the drawings, in which the appearance of the complete machine in full operation is clearly shown by the perspective view presented on Sheet 2, where the crude clay is represented in the act of being fed to the machine and the completed

brick delivered to the off-bearers. The machine is set in and supported by brick-work in the manner clearly shown in this figure.

In the drawings, A marks a stout frame of iron tied by braces B.

C is a short shaft, to which are attached the fast and loose pulleys D and E, to which the band from any suitable prime mover is applied. On the end of shaft C is cogged pinion F, gearing into cog wheel G on long shaft H. A pinion, I, on the end of shaft H engages with and drives main cog-wheel J on the main shaft K. Into this shaft are spirally inserted the tempering-blades c c, &c., and to its inner end is attached the conical screw L.

M marks the tempering or plugging chamber, which is cylindrical in form at the feed end and conical at the delivery end, as shown. It has an opening, Q, in the top for the introduction of the clay. Attached by bolts to the conical end of chamber M is conical screw-case N, in which the screw L works. The internal surface of this case is roughened or checkered, as shown in Fig. 1, for the purpose of preventing the clay from revolving in the case as the screw or flange revolves. The screw L, Fig. 9, is constructed so that the end at which the clay enters it is large in diameter, to receive the clay from the small end of the tempering-case, and gradually tapers toward the point, so as to deliver the clay at the center or on a line with the center of the shaft. The shaft or body of the screw L is reduced to a point at the outer end, and gradually increases in size, so that the area of the space between it and the large end of the screw-case is equal to the area of the small end of the case. Therefore the screw is capable of delivering at the point, and on a line with its center all the clay it receives at the base.

In order to insure the threads filling with clay, I put on an additional thread, l', commencing half-way round from the place of beginning of the main thread l and extending half-way round the base of the cone, so that it will deliver to the far side of the main thread all the clay it may receive. (See Figs. 9 and 11.) These figures give representations of the form of screw, which, from experience, I prefer to the simple spiral flange represented in Fig. 4 and lettered L. The compressing-die O is hinged to the smaller end of case N; its cross-section at its outer end is rectangular, as shown in Fig. 4; its inner end is round, as shown in Fig. 3, and a cross-section of its center is represented by Fig. 5. The corners are here seen rounded out or grooved, and these grooves gradually taper till they disappear at the angles of the outer rectangular opening of the die. The object of these grooves is to crowd a greater quantity of clay into the corners of the bar, so as to give them greater solidity and firmness, in accordance with the views hereinbefore stated. To this die O is attached a plain rectangular die, P.

The dies are lined with steel to diminish wear, and thus prevent irregularity in the size of the bricks. The outer end of the main shaft K works in a head-block, R, which is adjusted by bolts *b* and nuts *n*, and receives the backward thrust of the shaft. On long shaft H is placed hollow shaft Z, on one end of which is bevel-pinion S, meshing into bevel-wheel T on cross-shaft U. On the other end of this shaft U is pulley V, which, with pulley W, carries endless apron *a*. This apron, which sustains the weight of the bar of clay, H', is supported throughout its entire length by the small rollers *r*, &c. It is tightened when required by pulley X, Fig. 1, which is applied to its surface with any required degree of force by means of the lever *l*, operated by the foot and held in any desired position by the pins *p*. The apron *a* receives the bar of clay H' as it comes from the die P. To the outer end of hollow shaft Z is attached fly wheel Y, which runs on the shaft H loose, and carries the spring knife-stock K', (see Figs. 2 and 8,) to the end of which the knife *k* is attached by a hinge, *h*, Fig. 8. The shaft H is so geared that it makes more than one revolution while the bar of clay is moving the length of a brick. On the shaft H, close to the fly wheel Y, is made fast a friction wheel, O', upon which bears a spring, *s'*, which is attached to the hub of the fly-wheel Y and its pressure regulated by the screw passing through it. The tendency of the shaft H, with its friction-wheel O', (when in motion,) is to turn the fly-wheel Y more than one revolution while the bar of clay is moving the length of a brick; but as the fly-wheel is connected to the bar of clay by means of the hollow shaft Z, pinion S, wheel T, shaft U, band-wheel V, and endless apron *a*, (which is long enough to prevent the bar of clay from slipping upon it,) the fly-wheel is thus prevented by the clay from making more than one revolution, thereby keeping the fly-wheel, with its knife, under the control of the clay, the friction-spring *s'* on the friction-wheel O' being so regulated as to communicate sufficient power to the wheel to do the cutting off, but not so much as to overcome the resisting power of the bar of clay. Thus the knife *k* always cuts the bar into lengths exactly equal to each other without reference to the speed of the machine. The clay bar is supported at the line of section by a rectangular guide, L', Figs. 6 and 7, which the bar passes through a distance equal to the length of one brick previous to severance. Guide-bars G G' project up from L' to receive and guide the knife *k* in its passage to and through the bar of clay. The guide L' is attached to arm M' which is hinged at *e* to the lower framing I' of the machine, as shown in Figs. 6 and 7. It is allowed a short vibration, controlled by a spring, *f*, Fig. 6. It can thus move a short distance with the bar of clay H' while this is being severed by the knife *k*, and then is retracted to its standing-point by the spring *f* until the knife again enters the clay

at another revolution of fly-wheel Y. To relieve the knife from any pressure the moving bar of clay would exert against it while passing through, there is secured to the side of the frame an adjustable inclined plane, G², (see Figs. 1, 2, 6, and 7, and 10,) against which the knife-frame slides, thereby receiving on its descent a lateral motion, the inclination being just equal to the distance the clay moves during the passage of the knife through it. This lateral motion is communicated to the knife-guide or clay-support L', Figs. 6 and 7, by means of the clamps, between which the knife is secured passing between two horns or projections, G' G', Figs. 1, 6, and 7. Thus a simultaneous lateral motion of the knife with its guide and clay-supporter and the bar of clay is obtained. The knife *k* is a thin piece of tempered steel, Fig. 8, secured to the swinging cam *h* by bolts and clamp. This cam *h* is held in position by the spring *s* with just sufficient force to prevent the knife from turning with the resistance of the clay during its passage through it, but not with sufficient force to break the knife or stop the fly-wheel in case any foreign substance interfered with its passage, but will allow the knife to turn back, as shown in the dotted line in Fig. 8, to clear the obstruction, when it is brought to its original position by the eccentricity of the cam, which is so shaped that the spring will overcome the greatest resistance at the commencement of the backward motion. The arm K, in the end of which the knife-cam *h* turns, is secured to the fly-wheel Y in such manner as to admit of a slight lateral motion either by the spring of the arm, as represented, or it may work on centers and be held in position by a separate spring. The end of the bar of clay protruding through the knife-guide and clay-supporter is supported by a stationary platform, H³, the length of the protruding portion to prevent the off-bearing apron from parting the brick from the bar before it is severed entirely by the knife. The shaft H at its outer end carries pulley A', connected by a band, B', to pulley C' on short shaft D'. On this shaft is bevel-pinion E', gearing with bevel-wheel F', which has on its other end pulley V', which, with pulleys W' and W², (see Fig. 1,) carries the off-bearing apron *a'*, which is supported, like apron *a*, on small rollers *r*, &c., throughout its length. This apron is tightened when desired by pulley X', applied to it by means of lever *l'* in a precisely similar manner to that in which apron *a* has been already described as being tightened. The driving pulley V' of this apron is so geared that the apron is run considerably faster than apron *a*, the effect of which is to separate the bricks H² from each other by any desired interval as they pass onto this apron after being severed from the bar H'.

The operation of the machine is as follows: The machine being set in motion, the clay is fed into the tempering-chamber M through the opening Q, and is there thoroughly tem-

pered by the operation of the blades *c*, which gradually force it toward the conical end of the chamber until it is brought under the action of the spiral and conical flange or screw *L*, which presses it through the compressing-die into and through the forming-die, whence it emerges in the form of a continuous bar. By this power it is first thoroughly divided by the knives, compressed by being continually forced through the lessening size of the chamber; its contained air expelled, and the now compacted and solid, yet plastic, mass forced out in a perfectly homogeneous bar, whose sides and edges are smooth and firm. The bar is received upon the endless apron *a*, which, by its weight and adhesion, it thus governing the rotation of the pulley *V* and wheel *T*, shaft *X*, and fly-wheel *Y*, with its attached knife *k*, and these are so geared that the wheel *Y* will make one revolution while the bar moves the exact length of a brick. When the bar *H'* reaches and enters the guide *L'*, the knife *k* descends through the guides *G' G'*, and enters and severs the bar. The lever *K*, which carries the knife-cam, coming in contact with the inclined plane *G²*, receives a lateral motion just equal to the motion of the clay which it communicates to the guides *G' G'*, and thus to the knife-guide and clay-supporter, while the knife is passing through the clay, so that the relative positions of the knife and clay are not altered during the cutting or severing process, and the ends of the bricks are perfectly at right angles with the sides. The guide *L* and knife are immediately drawn back to their original positions by the spring *f* and the spring of the arm *k* as soon as the knife has passed through the bar. The severed brick is received on the stationary plate *H³*, from which it is pushed by the advancing bar of clay until the friction of the off-bearing apron is sufficient to draw it off, when it is received onto off-bearing apron *a'*, which, being geared to move faster than apron *a*, and being driven independently of the bar of clay by connection with shaft *F*, separates the bricks by a considerable interval and facilitates their removal by the off bearers.

I claim—

1. Arranging in the same horizontal line with each other the tempering chamber, impelling screw, and forming die, so as to secure directness of action and simplicity of gearing, as described.

2. Imparting to the tempering-chamber and screw-case the tapering form described and shown, so as to gradually compress the clay and exclude the air in its passage to the forming-die, as specified.

3. So constructing a screw that the clay may enter it at an annular space and be delivered in a solid mass opposite its end and at the center of the screw, substantially in the manner and for the purpose described.

4. Preventing the clay from revolving with the screw in the screw-case by roughening or checkering the interior surface of that case, substantially as described.

5. The combination of a knife with a fly-wheel for the purpose of severing a bar of clay into proper lengths for bricks, the velocity of said fly-wheel being regulated or controlled by that of the bar of clay.

6. The combination of the apron *a* with the fly-wheel *Y* and knife *k*, all arranged for joint operation, substantially in the manner and for the purpose specified.

7. Propelling the cut-off device by means of a friction-clutch, and regulating the power of said clutch by means of a yielding pressure.

8. The yielding severing-knife *k*, constructed and operating substantially as set forth.

9. Supporting the clay at the line of severance by a movable frame or supporting stirrup-guide, *L'*, through which the knife *k* is guided, as and for the purpose stated.

10. Moving the knife and the supporting-guide *L* together during the severance of the bar at the same speed with which the bar of clay advances, for the purpose of cutting off the brick at right angles to the course of the bar, as directed.

11. Driving the off-bearing apron *a'* at greater speed than that of the bar of clay, for the purpose of separating the bricks by a sufficient interval, as described.

12. Giving to the conical impelling-screw a gradual increasing depth or thread, to secure uniformity between the amount of clay received by the base of the screw and that delivered at its point, as set forth.

The above specification of my said invention signed and witnessed, at Philadelphia, this 18th day of December, A. D. 1862.
